Primary Examiner — Martie K Holtje(74) *Attorney, Agent, or Firm* — Stein IP LLC(57) **CLAIM**

The ornamental design for a drying tool, as shown and described.

DESCRIPTION

FIG. 1 is a top perspective view of a first embodiment of a drying tool showing my new design;

FIG. 2 is a bottom perspective view of FIG. 1;

FIG. 3 is a top perspective view of the exterior face of one of the triangular segments of FIG. 1;

FIG. 4 is a bottom perspective view of the interior face of the triangular segment of FIG. 3;

FIG. 5 is a top perspective view of the exterior face of the other triangular segment of FIG. 1;

FIG. 6 is a bottom perspective view of the interior face of the triangular segment of FIG. 5;

FIG. 7 is a top perspective view of a second embodiment of the drying tool of my design of FIG. 1;

FIG. 8 is a bottom perspective view of FIG. 7;

FIG. 9 is a top perspective view of the exterior face of one of the triangular segments of FIG. 7;

FIG. 10 is a bottom perspective view of the interior face of the triangular segment of FIG. 9;

FIG. 11 is a top perspective view of the exterior face of the other triangular segment of FIG. 7; and,

FIG. 12 is a bottom perspective view of the interior face of the triangular segment of FIG. 11.
